UNITED STATES PATENT OFFICE.

GREYDON N. ALWORTH, OF SOUTH MILWAUKEE, WISCONSIN.

AUTOMATIC LINE INDICATOR FOR TYPEWRITERS.

Application filed October 7, 1926. Serial No. 140,171.

This invention relates to an automatic line indicator for typewriters designed to indicate to the typist that the last line has been reached.

5 One of the principal objects of the present invention is to provide a device of this character which requires no adjustment but is automatically operated when the lower edge of the sheet of paper comes to a pre-
10 determined position on the platen of the typewriter.

A further object is to provide an automatic indicator for typewriters having these advantages and capacities and which is of
15 simple and durable construction, reliable and effective in operation and easy and comparatively inexpensive to manufacture.

Other objects and advantages reside in certain novel features of the construction,
20 arrangement and combination of parts which will be hereinafter more fully described and particularly pointed out in the appended claims, reference being had to the accompanying drawings forming a part of
25 this specification, and in which:

Figure 1 is a view in front elevation showing a typewriter carriage with an automatic indicator embodying the present invention,

Figure 2 is a sectional view on the line 30 2-2 of Figure 1,

Figure 3 is a similar view on the line 3-3 of Fig. 1 and illustrating one phase of the operation,

Figure 4 is a view similar to Fig. 3 showing another phase of the operation,

Figure 5 is a sectional view on the line 5-5 of Figure 1,

Figure 6 is a detail perspective view showing the principal parts of the attachment
40 illustrated in Figs. 1 to 4,

Figure 7 is a view in section showing another form of the invention,

Figure 8 is a view in end elevation of another modified form of the invention,

45 Figure 9 is a plan view of the modified forms shown in Fig. 8, and

Figure 10 is a view thereof in front elevation.

Referring to the drawings and more particularly to Figs. 1 to 6, inclusive, the numeral 1 designates generally a typewriter carriage which may be of any standard construction and which has the usual paper holding and feeding means. As usual the
55 paper holding and feeding means includes a

platen 2 fixed to a rotatable shaft 3, the shaft 3 being turned by the thumb pieces 4. Associated with the platen is an elongated generally arcuate shape paper guide 5 constructed of sheet metal and supported in the usual manner. The other instrumentalities of the paper holding and feeding means are well known and need no detailed explanation here. The present invention proposes the provision of a shaft 6 which extends along the guide 5 in substantial parallelism to the axis of rotation of the platen 2. At spaced points along this shaft 6 toothed paper engaging rollers 7 are fixed. The teeth of the rollers 7 are indicated at 7^a and as clearly shown in Figs. 3 and 4 these teeth 7^a are directed at an angle in the direction of rotation of the rollers and they serve to define pockets 8 in which the lower edge of the paper is caught as will 70 hereinafter be more fully described. The guide 5 is cut away adjacent each roller 7 so that the teeth of each roller 7 lie close up against the outer surface of the platen when the teeth are positioned in the open-
75 80 85 90 95 100 105 110

ings provided therefor in the guide 5. The shaft 6 is driven at a rate of speed greater than that of the platen and preferably the teeth of the rollers move about two and a half times as fast as the platen and the paper fed thereby but this speed ratio may be varied and especially may be increased with good results. For the purpose of so driving the shaft 6 the shaft 3 on which the platen is fixed also has fixed there-
85 90 95 100 105 110

suitably fixed to the frame 17 and the extremity of its long leg formed with a bearing opening in which the shaft 6 is rotatably fitted. The bearing bracket 16 may 5 be of U-shape and fastened to the frame 17 by the same bolts and nuts 18 employed to mount a bell 19 on this frame 17 or it may be a special elongated bolt head of bolt 18 with a hole drilled in its center to receive 10 the adjacent end of shaft 6.

A releasable driving connection is provided between the pinion 11 and the shaft 6 and this releasable driving connection may take the form of a ratchet 20 integral with 15 or suitably fixed to the pinion 11 and like the pinion 11 freely rotatable on the shaft 6. Around the periphery the ratchet wheel has a number of teeth 21, and with these teeth 21 a pawl 22 is engageable, the pawl 22 being pivoted, as at 23, on a plate 24 fixed to the shaft. A retractile coil spring 25 has one end suitably anchored to the plate 24 and has its other end connected to one extremity of the pawl 22. On the side 20 of its pivot opposite the spring 25 the pawl 22 is provided with an arm 26 and the extremity of the arm 26 is pivotally connected to one end of a link 27, the opposite end of the link 27 being pivotally connected to 25 an arm 28 provided on a striking frame assembly 29, the frame 29 having a pivotal mounting 30 on the plate 24. This frame 29 includes spaced side pieces 30 and 31 connected by a transverse connecting element 32, the connecting element 32 spanning the plate 24 and in this way disposing the side pieces of the striking frame on the opposite sides of the plate. A clapper or striker 33 is connected to the frame by means of a 30 stiff wire and is adapted to strike the bell 19 to sound the same at the proper time. A counterweight 34 is carried by the side piece 31 of the frame. The teeth 21 are of such 35 shape, that is, their faces are so inclined and the pawl 22 is of such a shape and is so designed that as long as there is no appreciable resistance to the turning of the shaft 6, this pawl and ratchet affords a 40 driving connection between the pinion 11 and the shaft 6, whereby the motion of the platen is transmitted at a higher rate of speed to the shaft 6. When, however, the 45 lower edge of the sheet S of paper in the typewriter comes into the position shown in Fig. 3 it snaps into one of the pockets 8 and as shown in Fig. 4, due to the biting of the paper S between the roller tooth 7^a and the stationary paper guide 5 resists 50 turning movement of the rollers 7 and consequently of the shaft 6. The clearance 55 between tooth 7^a and paper guide 5 should be about .002 of an inch or less than the thickness of ordinary typewriter paper.

65 This additional load imposed on the shaft

6 is sufficient to cause the pawl 22 to be disengaged or thrown out of contact with the teeth of the ratchet 21 and this movement of the ratchet is communicated to the striker frame through the arm 26 and link 70 27. When the striker frame moves it throws the clapper or striker 33 against the bell and sounds the signal, thereby advising the operator that the last line has been reached. This disconnection of the driving 75 connection afforded by the pawl 22 and ratchet 20 frees the shaft 6 and rollers 7 from their connection with the platen and permits the paper to readily disengage itself from the teeth of the rollers 7.

The form of the invention shown in Figs. 8 to 10 inclusive, is similar to that hereinabove described except that a different type of driving connection is employed between the pinion 11 and the shaft 6 and a different means is employed for supporting the bell and for sounding the bell when the driving connection is released. As shown in Figs. 8 to 10 the pinion 11 has a clutch member 40 fixed thereto and this clutch member 40 and pinion 11 are rotatably mounted on a smooth end portion of the shaft 6. In this form of the invention the frame 17 and bearing plates 15 and 16 are omitted and these several parts are replaced by a pair of bearing brackets 41 connected to a stationary part of the carriage and 80 rotatably supporting the smooth end portion of the shaft 6. A second clutch member 42 is co-operatively disposed with respect to the clutch member 40, the clutch members 40 and 42 having interfitting teeth. The clutch member 42 has a square opening through its hub in which a squared portion of the shaft 6^a is slidably and snugly fitted. The hub of the clutch member 42 has an extension 43 which engages one arm 44 of a bell crank lever, designated generally at 45, the bell crank lever is fulcrumed, as at 46, on a stationary part of the carriage or on a bracket connected thereto and it also has a long arm 48 connected by a link 49 to a crank arm 50 provided on one end of a rock shaft 51, the rock shaft being journaled in bearings provided therefor in a suitable bearing bracket 52. A striker 53 is fixed to the rock shaft and is co-operably disposed with respect to the bell 19 which may be supported in any desirable position 105 on the carriage.

The bell crank lever is biased to position to engage the extension of the hub by means of a compression spring member 55. This spring member 55 is not a retractile spring 115 but serves by expansion to keep the member 45 in direct contact with the reduced portion of the hub of the clutch member 42. In this form of the invention as in the other the toothed rollers are driven at a greater rate 120 125

of speed than the platen through the instrumentality of the gears 10 and 11 and in this instance by the driving connection afforded by the interengaged clutch members 40 and 42. When the lower edge of the sheet of paper is caught in one of the rollers the load thus imposed on the shaft 6 is sufficient to cause the clutch members 40 and 42 to slide apart inasmuch as the clutch member 42 is held while the clutch member 40 continues to rotate. As a result of this action the clutch member 42 is disposed inwardly along the shaft 6 and its cover extension 46 swings the bell crank lever 45 which in turn rocks the rock shaft 51 through the link 49 and swings the striker 53 to sound the bell. The operator is thus advised that the last line is reached.

In all forms of the invention no setting is necessary and the operation is entirely automatic. Backing up of the paper by reverse rotation of the platen causes no trouble even if the bell is about to ring due to the engagement of the tooth 7^a. Two rollers are shown but more rollers might be used to insure positive action. The bell may be of a different tone from the bell that indicates the end of a line if this is desirable. In either form the attachment may be manufactured at a comparatively slight expense and may be easily applied to the typewriter without the necessity of modifying the construction or mode of operation of the paper holding and feeding means. In forming the teeth 7 it is extremely desirable to round off all sharp edges to prevent tearing of the paper and if desired adjacent each toothed roller 7 a guide roller 75 may be placed as shown in Fig. 7. A roller placed at this point doubly insures the catching of the lower edge of the paper in the pocket and also facilitates the release of the paper from the pocket after the signal has been sounded.

I claim:

1. The combination with a typewriter carriage having paper feeding and holding means including a rotatable platen, of a shaft extending along and adjacent the platen, a roller fixed to the shaft and having teeth designed to engage and hold the lower edge of the paper, gearing for driving the shaft from and at a greater rate of speed than the platen, said gearing including normally interengaged elements automatically disengaged when the lower edge of the paper is caught, a signal, and means for actuating the signal when said elements are disengaged.

2. The combination with a typewriter carriage having paper feeding and holding means including a rotatable platen, of a shaft extending along and adjacent the platen, a roller fixed to the shaft and having teeth designed to engage and hold the lower edge of the paper, gearing for driving the shaft including a releasable driving connec-

tion automatically releasable when the lower edge of the paper is being caught, a signal, and means for operating the signal when said elements are disengaged.

3. The combination with a typewriter carriage having a paper feeding and holding member including a rotatable platen, of a shaft extending along and adjacent the platen, means for rotating the shaft, rollers fixed to the shaft and having teeth inclined in the direction of rotation of the rollers and forming pockets in which the lower edge of the sheet of paper in the typewriter is adapted to catch, gearing for driving the shaft from and at a greater rate of speed than the platen, said gearing including normally interengaged elements automatically disengaged when the lower edge of the paper is caught, a signal, and means for actuating the signal when said elements are disengaged.

4. The combination with a typewriter carriage having paper feeding and holding means including a rotatable platen, of a shaft extending along and adjacent the platen, means for mounting the shaft for rotary movement, rolls fixed to the platen and having means designed to engage and catch the lower edge of the sheet of paper in the typewriter, a large gear wheel connected to and driven by the platen, a pinion loosely mounted on the shaft and meshed with the large gear wheel, a releasable driving connection between the pinion and the shaft including interengaged elements adapted to be automatically disengaged when the lower edge of the paper is caught, a bell mounted on the carriage, and a striker for the bell having means connected thereto and operable by the disengagement of said members.

5. The combination with a typewriter carriage having a paper feeding and holding means including a rotatable platen, of a shaft extending along and adjacent the platen, means for mounting the shaft for rotation, rolls fixed to the platen and having teeth designed to engage and catch the lower edge of the paper, a large gear wheel connected to the platen and driven thereby, a pinion loosely mounted on the shaft and meshed with the large gear wheel, a ratchet wheel connected to the pinion, a plate fixed to the shaft, a pawl pivoted to the plate and engageable with the ratchet wheel, a light spring for holding the pawl engaged with the ratchet wheel, a striker frame pivoted to the plate, and connected with the pawl, said striker frame having a counterweight, a striker carried by the striker frame, and a bell co-operable with the striker.

6. The combination with a typewriter carriage having a paper feeding and holding means including a rotatable platen, of a shaft extending along and adjacent the platen, means for mounting the shaft for

- rotation, rolls fixed to the platen and having teeth designed to engage and catch the lower edge of the paper, a large gear wheel connected to the platen and driven thereby, a pinion loosely mounted on the shaft and meshed with the large gear wheel, a ratchet wheel connected to the pinion, a plate fixed to the shaft, a pawl pivoted to the plate and engageable with the ratchet wheel, a light spring for holding the pawl engaged with the ratchet wheel, a striker frame pivoted to the plate and connected with the pawl, a striker carried by the striker frame, and a bell co-operable with the striker.
7. The combination with a typewriter carriage having a paper feeding and holding means including a rotatable platen, of a shaft extending along adjacent the platen, means for mounting the shaft for rotation, rolls fixed to the shaft and having teeth designed to engage and catch the lower edge of the paper, a large gear wheel connected to and driven by the platen, a pinion loosely mounted on the shaft and meshed with the large gear wheel, a clutch member fixed to the pinion, a second clutch member splined on the shaft, said clutch members having co-operable teeth designed to normally connect the clutch members but operating to automatically shift the second clutch member along the shaft when the lower edge of the paper is caught in the teeth of the rolls, a bell, a striker for the bell, and means for causing the striker to hit the bell when the second clutch member is disengaged from the first-mentioned clutch member.
8. The combination with a typewriter carriage having paper feeding and holding means including a rotatable platen and a

guide plate associated with the platen, of a shaft extending along and adjacent the platen, means for mounting the shaft for rotation, rolls fixed to the shaft, said guide having openings adjacent each roll, each roll having teeth designed to engage and hold the lower edge of the sheet of paper in the typewriter, a guide roller adjacent each roll, gearing for driving the shaft from and at a greater rate of speed than the platen, said gearing including normally interengaged elements automatically disengaged when the lower edge of the paper is caught, a signal, and means for actuating the signal when said elements are disengaged.

9. The combination with a typewriter carriage having paper feeding and holding means including a rotatable platen, of a shaft extending along and adjacent the platen, means for mounting the shaft for rotation, rolls fixed to the shaft and having teeth designed to engage and hold the lower edge of the paper, a large gear wheel connected to and driven by the platen, a pinion meshed with the large gear wheel and loosely fitted on the shaft, a driving connection between the pinion and the shaft including an element connected to the pinion, and a co-operable element connected to the shaft, means for normally maintaining the elements engaged by permitting the co-operable element to move out of engagement with the element connected with the pinion when the lower edge of the paper is caught in the teeth of the rolls, a bell, and means operated by the movement of the co-operable element for sounding the bell.

GREYDON N. ALWORTH.
